Atty.

UNITED STATES PATENT OFFICE

ALBERT J. HANSON, OF ARLINGTON, MASSACHUSETTS

ELECTRIC FURNACE

Application filed December 31, 1930. Serial No. 505,780.

This invention relates to an electric furnace and particularly to a novel means for supporting an electric heating element therein.

- 5 In certain types of electric furnaces, particularly those of large area where a heating element or resistor is employed that has a plurality of convolutions embodied therein, it is essential that the roof resistor shall 10 be so supported that the numerous convolutions cannot sag. Furthermore, as it is necessary to repair or replace these resistors frequently, it is very important that they be mounted in such a manner that they may be 15 easily and quickly removed from the heating chamber, detached from the various members with which they are associated, replaced and reinserted in the furnace without causing a prolonged shut-down of the furnace.
- 20 The object of this invention, therefore, is to provide an improved support for an electric heating element or resistor, said support being of simple construction and embodying therein a permanent portion that is embedded 25 in the lining of the furnace and a removable portion consisting of a plurality of interchangeable sections capable of being easily and quickly assembled as they are being inserted in the furnace or dismantled as they 30 are being removed from the furnace without it being necessary for the workmen who are performing these operations to enter the furnace.

Another object of the invention is to provide 35 a structure which will effectively support the various convolutions of a ribbon type resistor, or any other type of resistor that has a plurality of convolutions embodied therein, in such a manner that none of the 40 convolutions will sag.

The invention consists in an electric furnace as set forth in the following specification and particularly as pointed out in the claims thereof.

45 Referring to the drawings:

Fig. 1 is a horizontal section through a furnace, an electric heating element and supporting means therefor embodying my invention being illustrated mounted therein.

50 Fig. 2 is a vertical sectional elevation of

the upper portion of the furnace taken on the line 2—2 of Fig. 1.

Fig. 3 is a transverse section of the upper portion of the furnace taken on the line 3—3 of Fig. 1.

Fig. 4 is a perspective view of one of the insulators.

Fig. 5 is a perspective view of a spacing member.

Like numerals refer to like parts throughout the several views of the drawings.

In the drawings, 5 represents a furnace which may be constructed in any suitable manner from layers of heat-resisting materials all well known in the art. The furnace 5 is provided with a heating chamber 6 which is lined throughout with heat-resisting material 7.

The structure of this invention is provided for the purpose of supporting a roof heating element or resistor at the top of the heating chamber 6 and embodies therein a permanent portion which is built into the furnace and a removable portion which may be easily and quickly removed from the heating chamber when repairs or replacements are required. The permanent portion of the structure embodies therein a plurality of U-shaped brackets 8, legs 9 of which are embedded in the material of the lining 7. The brackets 8 are positioned end to end upon opposite sides of the heating chamber 6, but the adjacent brackets are spaced a short distance apart to allow for expansion. The brackets 8 project from the side wall of the lining inwardly and downwardly and have guideways 10 formed thereon upon which a plurality of supports 11 may rest and upon which said supports may be moved forwardly and rearwardly.

The supports 11 may be of different lengths, if it is so desired, and abut together end to end. They are furthermore interchangeable upon the brackets 8 and are connected together by means of inverted U-shaped couplings 12, the legs of which project through holes 13 that are provided in both ends of the supports. The supports 11 are of skeleton construction in order that heat may radiate therethrough, but said sup-

ports have solid portions 14 extending longitudinally thereof provided with grooves 15 therein in which insulators 16, illustrated in Fig. 4, may rest loosely and abut together end to end.

The insulators 16 are provided with transversely extending grooves 17, see Fig. 4, in which an electric heating element or resistor 18 may rest. The resistor 18, which is of a type commonly known as a ribbon resistor, is constructed in a single piece and embodies therein a plurality of convolutions 19, and the insulators 16 are so supported upon the supports 11 that the opposite end portions of each convolution will be supported in a manner to prevent it from sagging. The extremities of the resistor 18 are connected to terminals 20 which are located near the front of the furnace, said terminals projecting through openings 21 that are provided in the wall of the furnace. A wire 22 of an electric circuit is attached to the outer extremity of each terminal 20.

Spacers 23, illustrated in detail in Fig. 5, are interposed between the two side portions of the resistor 18 and abut together end to end. The spacers 23 embody therein horizontal flanges 24 which rest upon the convolutions 19 of the resistor and a portion 25 which projects downwardly between these convolutions and holds them spaced apart. The insulators 16, furthermore, hold the various convolutions 19 of the resistor 18 spaced relatively to each other. The total width of the resistor 18 is slightly less than the width of an entrance 26 to the heating chamber 6 and said resistor is adapted to be inserted lengthwise through said entrance and extend from the front to the rear of the heating compartment.

In assembling the structure the supports 11 are placed upon the guideways 10 of the brackets 8, the successive supports being coupled together as they are pushed rearwardly along the guideways. After a support 11 has been laid upon the front pair of brackets 8 the insulators 16 are placed in the grooves 15 provided therefor and the rear portion of the resistor is then placed in position upon the insulators, the various convolutions 19 of the resistor being located in their proper grooves in the insulators. In this manner all of the supports 11 and insulators 16 are successively placed in position and the successive convolutions 19 of the resistor 18 are placed in position upon the insulators until the entire structure has been assembled and pushed rearwardly upon the various brackets 8 and the resistor is located in position in the heating compartment, the entire operation being completed without it being necessary for the workmen, who are performing the operation, to enter the heating compartment.

Whenever it is necessary to dismantle the

structure, the various units thereof are pulled forwardly through the entrance 26 of the furnace and separated as they are being removed, and in performing this operation it is not necessary for the workmen to enter the furnace.

Although the support of this invention is illustrated and described as being employed in connection with a ribbon type resistor, it is evident that the resistor does not necessarily need to be constructed of ribbon material as the support may be easily adapted to receive other well known forms of resistors without departing from the spirit of this invention.

I claim:

1. In an electric furnace a lining, brackets embedded therein, supports slidable upon said brackets, means to couple said supports together, whereby movement may be transmitted from one support to another in opposite directions and a resistor positioned upon said supports.

2. In an electric furnace a lining, brackets embedded therein, supports slidable upon said brackets, means to couple said supports together, whereby movement may be transmitted from one support to another in opposite directions, insulators mounted upon said supports, and a resistor mounted upon said insulators.

3. An electric furnace embodying therein a heating chamber provided with an entrance thereto at the front thereof, brackets embedded in the side walls of said chamber and provided with guideways thereon, supports insertable through said entrance and slidable upon said guideways, and an electric heating element for the top of said chamber also insertable through the entrance and positioned upon said supports.

4. An electric furnace comprising, in combination, a heating chamber, brackets mounted therein provided with guideways thereon, supports resting loosely upon said brackets and slidable upon said guideways, means to couple said supports together, whereby movement may be transmitted from one support to another in opposite directions, insulators seated upon the supports, and a resistor positioned upon said insulators.

5. An electric furnace comprising, in combination, a heating chamber, brackets mounted therein at the side thereof and provided with guideways thereon extending longitudinally of said chamber, supports resting loosely upon said brackets and slidable longitudinally of the chamber upon said guideways, said supports being provided with grooves therein, insulators seated within said grooves and also provided with grooves therein, and a resistor mounted upon said insulators and seated within said last-named grooves.

6. An electric furnace comprising, in com-

5 combination, a heating chamber, brackets embedded within the side walls thereof and provided with guideways thereon longitudinally of said chamber, supports resting upon said brackets and slideable upon said guideways, said supports being provided with grooves therein, U-shaped means to couple said supports together, insulators seated within said grooves and also provided with grooves therein, and a resistor mounted upon said insulators and seated within said last-named grooves.

10 7. An electric furnace comprising, in combination, a heating chamber, brackets embedded within the side walls thereof and provided with guideways thereon, supports resting upon said brackets and slideable upon said guideways, said supports being provided with grooves therein, means to couple said supports together, whereby movement may be transmitted from one support to another in opposite directions, insulators seated within said grooves and also provided with grooves therein, a resistor mounted upon said insulators and seated within said last-named grooves, and members resting upon said resistor and spacing portions thereof apart.

15 20 25 In testimony whereof I have hereunto set my hand.

30 ALBERT J. HANSON.
